UNITED STATES PATENT OFFICE.

PAUL THEODOR SIEVERT, OF DRESDEN, GERMANY.

PROCESS AND MACHINE FOR FORMING GLASS ARTICLES.

No. 825,161.

Specification of Letters Patent.

Patented July 3, 1906.

Original application filed January 7, 1905, Serial No. 240,003. Divided and this application filed January 9, 1906. Serial No. 285,247.

To all whom it may concern:

Be it known that I, PAUL THEODOR SIEVERT, a citizen of the German Empire, and a resident of Dresden, Germany, have invented 5 certain new and useful Improvements in Processes and Machines for Forming Glass Articles, of which the following is a specification.

My invention relates to a process of and apparatus for forming hollow glass articles, and particularly for forming glass cylinders or other articles the lower end of which is to be open.

In a companion application, Serial No. 15 240,003, filed January 7, 1905, of which application this is a division, I have shown a process of and method for blowing hollow glass articles. That invention is well adapted to the blowing of glass cylinders from which 20 plate or sheet glass is made and similar articles which require to be opened at their lower ends. The present invention provides a convenient way of producing this opening and of assisting in the extension of the article during the process of forming the same.

In the drawings, Figure 1 is a vertical elevation, partly in section, of a glass-forming apparatus embodying my invention. Fig. 2 is a side elevation of the machine, the parts 25 being disposed in different position and certain parts being, as before, in section. Fig. 3 is a partial vertical section showing the device in operation. Fig. 4 is a similar section showing a modified form of the device. Fig. 35 5 is a vertical section of a mold which may be used in connection with my invention. Fig. 6 is a top plan view, and Fig. 7 a vertical section, of a mold of somewhat modified construction.

40 1 designates a carrier consisting of a frame which may have any desired form and which, as shown, is suspended from a shaft 2, rotatably supported on a frame 3. The rotation of the shaft is effected through a worm-gear 4, which is driven by any suitable motor, shown as an electric motor 5. The frame 3 is capable of vertical motion in the main frame 6 of the machine and is suspended by a cable 7, which runs over a winch 8 and carries at its free end a suitable counterpoise 9. The winch 8 may be rotated by means of a 45 motor 10, whereby the slide-frame 3 and the

carrying-frame 1 are raised and lowered as desired.

11 designates a mold into which the molten metal is poured, which mold rests upon a carriage 12, running upon rails 13. The molten metal is poured into the mold 11, which is then run under the machine-frame 6 and brought into vertical alignment with the 60 frame 1. The frame is then lowered upon the mold 11, as shown in Fig. 1, the frame preferably having been previously heated, which may be conveniently accomplished by lowering it into the heating-chamber or fire-drum 18. The molten metal or mass of glass now becomes engaged with the frame 1, so that it will remain suspended from the frame when the latter is raised.

In the application above named, of which 70 this is a division, the parts are suffered to remain in the position shown in Fig. 1, in which the frame 1 rests upon the edges of the mold 11 until the molten metal 14 has cooled down, so that that portion thereof resting 75 upon the central portion of the mold is below the flowing-point. The carrier 1 is then raised to the position shown in Fig. 2 of the drawings, lifting the glass cake out of the mold 11, the cake, although still plastic, being 80 sufficiently cooled so that it remains in an approximately level form, as shown. Cooling means, as a channel 15 in the mold 11 or a channel 16 in the frame 1, may be provided, 85 if desired.

In the operation of my present process and of the apparatus herein shown it is of course unimportant whether the partial cooling of the glass mass while it still remains in the mold takes place or not. If the glass is so 90 cooled, it is necessary after the removal of the mold, which is performed by sliding the carriage 12 out of the way, to reheat it by lowering the frame 1 with the glass attached thereto into the heating-chamber 18. On the 95 glass being again raised it begins to extend by gravity, which may, if desired, be assisted by the introduction of a fluid under pressure through the passage 28 into the upper part of the frame 1 above the glass cake.

100 At any desired point, preferably when a cylinder of considerable length has been formed, as shown in Fig. 3 of the drawings, the plate 34, which is shown as pivotally sup-

ported by a bolt 35 in one of the covers 19 of the heating-furnace 18, is turned, by means of a key or other convenient means, to the position shown in Fig. 3 of the drawings. The article 14 is then lowered, so as to rest on the plate 34, so that its lower portion adheres thereto. This adhesion will be assisted by the heat rising from the chamber 18. The plate 34 is shaken by a blow with a hammer or otherwise or then suddenly cooled, as by a jet of water or cold air, when the bottom of the article or cylinder 14 will be cracked off, whereby the bottom of the cylinder is opened. The plate 34 may then be swung to its position shown in Fig. 1 of the drawings and the cylinder 14 reheated by lowering it into the chamber 18. The lower portion of the article 14 will then expand, forming a substantially cylindrical shape for its entire length. It will be seen that the upper portion of the chamber 18 is provided with a recess 36 for the reception of the plate 34 when not in use and that the cover 19, to which the plate 34 is eccentrically attached, is provided with a depending flange 37 to prevent escape of heat through the recess 36.

In the form of my device shown in Fig. 4 of the drawings the plate 34 is provided with an upwardly-extending lug or pin 38, on which rests a loose plate 39. It is evident that the former operations being performed, the article 14 on being raised will carry with it the plate 39. This may be lowered with the article 14 into the heating-chamber 18, so that when the article 14 is raised for further extension the weight of the plate 39 will assist in this operation. At any desired time the plate 39 may be quickly cooled or shaken, as before described, in which case the bottom of the cylinder will be cracked off as before.

A further modification is shown in Fig. 5 of the drawings, in which the mold 11, in which the metal is originally poured and in which the cake is cast, is provided with a plate 39, similar to that shown in Fig. 4. The plate in this case is set in a suitable recess in the bottom of the mold 11. It is evident that when the plate is lifted from the mold by the first raising of the carrier 1 this plate will be raised therewith and will consequently act to assist in developing and extending the cylinder made from the glass cake 14 and that it can be cracked off when desired.

The mold shown in Figs. 6 and 7 of the drawings is particularly adapted to the making of a cake of glass from which a rectangular vessel having two flat sides is afterward to be made. In this case a suitable recess in the bottom of the mold is occupied by a plate 39^a, which, as before, adheres to the bottom of the glass case. In this case it is of course understood that the periphery of the frame or carrier 1 will be in the form of a rectangle substantially like the plate 39^a, so that the glass

article when extended will have two large flat sides each capable of making when properly cut a sheet of glass.

It is evident that various other modifications may be made in the form of the device necessary to carry out the process of the invention without departure therefrom and that, so far as the claims to the device itself go, modifications may be made in the form shown without departing from the same. 75

What I claim is—

1. A process of manufacturing hollow glass articles having open lower ends which comprises: casting the metal in a mold, attaching to the periphery of the cast cake or mass a suspended carrier-frame, raising the glass mass from the mold by means of the carrier, treating the mass to extend its walls downwardly, attaching to the lower portion of the mass either before or after its extension a metal plate, and cracking off the lower end of the glass mass after its extension. 85

2. A process of manufacturing hollow glass articles having open lower ends which comprises: casting the metal in a mold, attaching to the periphery of the cast cake or mass a suspended carrier-frame, raising the glass mass from the mold by means of the carrier, attaching to the lower portion of the mass a metal plate, raising the glass mass and 90 the plate so that the weight of the plate acts to extend the mass, and cracking off the lower end of the mass after its extension. 95

3. A process of manufacturing hollow glass articles having open lower ends which 100 comprises: casting the metal in a mold provided with a loose plate at its lower portion, attaching to the periphery of the cast cake or mass a suspended carrier-frame, raising the cast mass with the plate adhering thereto 105 from the mold, moving the mass to secure the downward extension of its walls assisted by the weight of the plate, and cracking off the lower end of the mass after its extension. 110

4. A machine for manufacturing hollow glass articles comprising: a mold for casting a glass mass, a suspended carrier-frame for attachment to the periphery of the mass while the mass is in the mold, means for raising the frame, means for removing the mold from beneath the frame, and a plate positioned to be attached to the lower part of the mass. 115

5. A machine for manufacturing hollow glass articles comprising: a mold for casting 120 a glass mass, a suspended carrier-frame for attachment to the periphery of the mass while the mass is in the mold, means for raising the frame, means for removing the mold from beneath the frame, and a loose plate 125 positioned to be attached to the lower part of the mass. 130

6. A machine for manufacturing hollow glass articles comprising: a mold for casting a glass mass, a loose plate in the bottom of 130

said mold, a suspended carrier-frame for attachment to the periphery of the mass while the mass is in the mold, means for raising the frame, means for removing the mold from beneath the frame with the plate adhering thereto to the bottom of the mass, and a heating-chamber below and in vertical alignment with the frame.

In testimony whereof I have signed this specification in the presence of two subscribing witnesses.

PAUL THEODOR SIEVERT.
